DESIGN FOR A STEAM SYSTEM CONTROL UNIT FOR RETURN OF CONDENSATE TO BOILER

Louin Tiller, Chicago, Ill.

Application August 21, 1947, Serial No. 140,971

Term of patent 14 years

(Cl. D81—2)

To all whom it may concern:

Be it known that I, Louin Tiller, a citizen of the United States of America, and resident of Chicago, county of Cook, State of Illinois, have invented a new, original, and ornamental Design for a Steam System Control Unit for Return of Condensate to Boiler, of which the following is a specification, reference being had to the accompanying drawing, forming a part thereof, wherein:

Fig. 1 is a front perspective view of a steam system control unit for return of condensate to boiler, showing my new design; and

Fig. 2 is a rear perspective view thereof.

What I claim is:

The ornamental design for a steam system control unit for return of condensate to boiler, substantially as shown.

LOUIN TILLER.
